STROKING-MASSAGE APPARATUS

Karoline (Karla) Prohaczka and Stefan Prohaczka,
Vienna, Austria

Application February 17, 1953, Serial No. 337,414

2 Claims. (Cl. 128—24.1)

This invention relates to stroking-massage apparatus. There are already known some apparatus for stroking-massage in which, in a casing, a heating resistance—e. g. a filament-lamp (incandescent lamp)—is placed behind a cap or lens, consisting of a material permeable to light and heat, the position of which can be adjusted in relation to this lamp. Massage is effected with these apparatus by holding the casing and stroking with its cap or lens the part of the body to be treated.

In the case of the stroking-massage apparatus forming the object of this invention an improvement of these, already known types is achieved by screwing the cap, designed preferably as a convexo-concave lens with its concave side turned outward, on a detachable jacket made of a heat-retaining material, favorably of asbestos-Bakelite.

The casing may likewise be made of asbestos-Bakelite, in which case the casing should be constructed so as to consist of two parts.

By this construction of the casing the energy emitted by the filament lamp undergoes a directing effect whereby, on the one hand, radial emission of energy is prevented by the heat-retaining jacket and, on the other hand, a concentration of the emitted light and heat rays is achieved by the lens-like form of the cap. The concave outside face of the cap provides, at the same time, the sucking action which is of beneficial effect for the massage.

A further object of the invention consists of making the cap of synthetic resin, preferably methylmethacrylate also known as Plexiglas (safety glass, toughened glass) of blue color.

The surfaces of the concave side of the lens may show various radii of curvature. The edge of the hood may be bulged in order to enable treatment of cavities in the surface of the human body. A groove may also be machined into the inner surface of the hood for puttying.

According to the invention provision has been made to unite the cap or lens with the jacket into one single piece by means of a warm pressing process.

The directive effect brought about by the use of a casing of asbestos-Bakelite can still further be augmented by providing the sides of the filament lamp bulb with a metallic coating, preferably on the inside, silver being particularly suitable for this purpose.

The jacket bearing the cap may be fastened to the casing, in the way of a bayonet fastening, by means of a pin gliding in an angular slot.

Preferably the bottom of the casing bearing the filament-lamp, is, according to the invention, pierced through by an opening running parallel to the sockets for the insertion of the contact plugs of the filament-lamp; into this opening a pin or the like is inserted which allows the filament-lamp to be adjusted within the casing or to be removed from it.

The socket of the lamp may be provided with a separating rib reaching through between the sockets serving for the insertion of the contact plugs, and preventing both sparking over and inserting the lamp too deeply.

These and other characteristics of the subject matter of the invention come forth from the drawings which illustrate by way of examples three constructional forms thereof. Figs. 1 and 2 show axial sections of the first 5 constructional form, on planes perpendicular to one another. Fig. 3 is a top view of Fig. 1, with the lamp, jacket and hood removed. Figs. 4 and 5 visualize the plug associated with the apparatus, in two axial sections perpendicular to one another. Fig. 6 is a top view of Fig. 4, 10 with the casing removed. Axial sections of the second and third constructional forms are shown in Figs. 7 and 8, respectively. Fig. 9 is a schematic diagram of a switchbox fitted in the cord.

According to the first constructional form the casing 15 consisting of Bakelite or the like preferably of blue colour bears at its base a socket 2 into which the plug-sockets 3 and 4 are pressed; they are separated spark-proof by a rib 2a of the base-socket. In between them and the screwed plug-sockets 5 and 6 which are inserted into them 20 contact blades 7 and 8 are clamped; the leads-in 9 and 10 of a cable 11 which leave the casing through the ring 12 are connected to these contact blades.

The plugs 13, 14 of the holder 15 of a filament lamp 16 are inserted into the sockets 3, 4 or into the screwed 25 sockets 5, 6 until the lamp rests on the insulating rib 2a. The base of the casing is pierced within this rib by an axial opening (or bore) 17.

The filament lamp is surrounded by a jacket 18; this jacket has an angular slot 19 catching with the pin 20 30 of the casing.

The jacket 18 has at its outer end a screw-thread 21 serving for the screwing on of a cap 22 of blue synthetic resin, also known as Plexiglass, or the like. By an outer, concave face 23 and an inner, somewhat more bent face 24 the front of this cap is shaped in the way of a convexo-concave lens. Each face of the lens has varying radii of curvature. Between casing 1 and jacket 18 or cap 22 is placed a packing ring 25.

The jacket together with the cap may easily be connected to the casing or separated therefrom by means of the bayonet-lock-like fastening consisting of the slot 19 and the pin 20.

The filament-lamp may be easily shifted within the casing or removed from it by inserting from without a pin, a knitting needle or the like into the opening 17 and shifting or removing thereby the lamp.

By screwing the cap 22 on the jacket 18 a focal adjustment of the lens consisting of the faces 23 and 24 is made possible; thereby the apparatus may be used either as a point-irradiating device for deep-treatment, or as a surface-irradiating device with a greater dispersive action.

It is preferable to make the thermic jacket 13 of asbestos-Bakelite which will screen off heat emission in a radial direction.

With the second constructional form the edge 48 of the hood 47 is provided with a bulge which enables treatment of cavities in the surface of the body. A groove 49 is provided inside the hood for puttying 50. The side walls of the filament lamp 51 are coated with silver, on the inside of the bulb, which prevents radiation of energy 60 toward the sides.

According to the third constructional form the casing consists of a bottom part 53 and top part 54, the latter is in the form of a jacket made of asbestos Bakelite. This jacket is screwed to part 53 by means of a screw thread 55. The hood 56 is screwed to the jacket 54, and may also be secured in place by spreading a layer of putty 50 (see Fig. 8, at right). When parts 54 and 56 are unscrewed together from the base 53, the filament lamp 51 may readily be removed.

The plug which is to be used preferably for the stroking-massage apparatus according to the invention consists of

a base plate 26 made of Bakelite or the like into which the pins 27 and 28 are pressed in. Their back square end 29 and 30 have axial thread-bores into which the fastening-screws 31 for the casing 32 can be screwed. In order to prevent the fingers of the person operating the plug from touching the screws 31 the hollows of the casing 32 which accommodate the screw-heads are closed by screwed-in plugs 33 made of an insulating material.

The cable 11 with the lines 9 and 10 enters the casing through the ring 34. The line 9 is connected to a contact blade 35 which is assembled with the square 29 by the screw 36. The line 10 is in connection with a small plate 37 clamped between two nuts 38 of a bolt 39; this bolt and also the pins 27 and 28 are pressed into the base plate.

The switch lever 40 can be turned round the pin 39. A contact blade 41 and the projection of a socket of the resistance 43 are fastened to the square 30 with a screw. The other socket 45 of the resistance is connected with the small plate 37 by means of a wire connection 46.

In the position of the lever 40 which is drawn with full lines in Fig. 6 the electrical current entering for instance through the pin 28 takes its way through the resistance 43 into the line 10 while, when the lever is turned into the position as shown in Fig. 6 by dot-and-dash lines, the lever touches the contact plate 41 and the resistance 43 is short-circuited. Fig. 5 shows the lever 40 in its middle position.

Instead of placing the switch in the plug, a switch-casing 61 with lever 62 can be mounted in the cable 59, 60 leading from the plug 57 to the filament-lamp 58 (Fig. 9). By turning the same the switch 63 is either in open or closed position. When the switch is opened the current flows over the resistance 64, so that the lamp 58 then lights with reduced tension.

Normally the stroking-massage apparatus is used with short-circuited resistance and then the filament-lamp produces, as an example, ten lux. When that temperature is reached which gives the body the most pleasant feeling the resistance 43 is switched in whereupon the current will only compensate the radiation losses and the temperature will remain constant.

By suitably adjusting the form and the dimensions of the apparatus it can be used also for all cavities of the body, e. g. throat, ears, intestine, urinary passage, and female cavities. In this cases it will generally be necessary to build in a still greater resistance than for the treatment of the surface of the body.

If three sockets are provided instead of two the apparatus according to the invention may be fitted with a lamp giving light at option with two different outputs (Bilux lamp).

What we claim is:

1. Stroking massage apparatus comprising a casing having an open end and a bottom with an opening, a cap fitting the open end of the casing and including a concave-convex lens, the inner lens side being convex and the outer lens side being concave, a jacket detachable from the lens and of asbestos Bakelite, an incandescent lamp mounted in the bottom of the casing and including contacts, sockets provided in the casing bottom on either side of the opening and each fitting a contact, the opening in the casing bottom permitting the insertion of a pin and the like for shifting the lamp within the casing.

2. Stroking massage apparatus comprising a casing having an open end and a bottom, a cap fitting the open end of the casing and including a convex-concave lens, the inner lens side being convex and the outer lens side being concave, a jacket detachable from the lens, a lamp mounted in the bottom of the casing and including contacts, the casing bottom having sockets each fitting a contact and a separation rib between the sockets and contacts and preventing sparking over between the contacts and the too deep insertion thereof into the sockets.
